LOCOMOTIVE STOKER

Charles J. Surdy, Tuckahoe, N. Y., assignor to
 The Standard Stoker Company, Incorporated,
 a corporation of Delaware

Application December 31, 1936, Serial No. 118,517

2 Claims. (Cl. 110—104)

This invention relates to stokers of the type which feed through an opening in an upright wall of a furnace. More particularly, the invention is directed to certain improvements in the 5 construction of stokers for installations to existing locomotives in which the hollow backhead of the firebox is provided with a firing opening of conventional form and size.

In stokers of the type referred to herein, it 10 has heretofore been proposed to feed the fuel through the existing opening in the firebox backhead. However, in these proposed stokers, the fuel projecting and distributing means is usually disposed at the firing opening in the firebox back- 15 head, thereby restricting, to a greater or lesser extent, the effective size of the firing opening when access in to the interior of the firebox is necessary.

Therefore, it is the principal object of this in- 20 vention to improve the above conditions by the provision of a stoker which feeds fuel through the firing opening onto a fuel distributor passing through said backhead subjacent said firing opening.

25 A further object of this invention resides in the provision of a tube passing through the hollow backhead subjacent the firing opening through which tube the fuel distributor extends into the firebox.

30 It is also an object of this invention to provide novel and efficient means for positioning said distributor subjacent the firing opening.

A still further object resides in the provision, 35 in a stoker which feeds fuel through the firing opening, of a pair of independently operable fuel deflector vanes which are so formed that upon being retracted, said vanes conform with the curvature of the firing opening whereby access to the interior of the firebox may be had in a 40 convenient manner.

These and other objects, aims and advantages 45 of the present invention will become apparent as the following description thereof is read in connection with the accompanying drawing, in which,

Fig. 1 is a central vertical section through the firing opening of a locomotive firebox backwall showing the stoker according to the present invention in position, portions thereof being in section and other portions in side elevation;

Figures 2 and 3 are sectional views taken on the lines 2—2 and 3—3, respectively, of Fig. 1; and

Fig. 4 is a view taken on the line 4—4 of Fig. 3 showing the fuel distributor in plan.

On the drawing, 10 designates a locomotive, 11 the boiler thereof, and 12 the hollow backhead including the outer sheet 13 and the inner sheet 14. At a suitable distance above the cab deck 15 and the grates 16 of the firebox 17, the inner and outer sheets are flanged inwardly toward each other to form the conventional firing opening 18. This firing opening 18 is usually elliptical in shape, having a major axis of approximately twenty (20) inches and a minor axis of approximately sixteen (16) inches. It is to be understood that in some instances these dimensions will vary.

A fuel feeding device for transferring fuel from the tender to the locomotive is shown generally at S and comprises an elevating conveyor 19 on the locomotive and a conveyor 20 leading forwardly from the tender (not shown). The conveyor 20 delivers fuel to the elevating conveyor 19 at a point below the cab deck 15 and is flexibly connected to said conveyor 19 by a universal joint 21.

The elevating conveyor 19 comprises a tubular conduit portion 22 and a casing portion 23 which surmounts the conduit portion 22 and embraces the firing opening 18. Bolts 24 passing through the flanges such as 25 of the casing 23 secure the same to the backhead 12. At its lower end, the tubular conduit 22 is provided with a flange 26 which is secured to a bracket 27 carried by the backhead 12 and the mudring 28. The casing 23 includes the upper wall 29 and side walls 30, the outer marginal edge 31 of which together with the upper edge 32 of the tubular conduit 22 define an aperture 33 opposite the firing opening 18. A firedoor 34 is supported by the casing 23 and forms a movable closure for the aperture 33. Since the firedoor 34 is of the well known "Franklin Butterfly" type, detail description thereof is not deemed to be necessary.

The tubular conduit 22 comprises a bottom wall 35, the upper end of which terminates short of the backhead 12 and the firing opening 18. A lip 36 is formed at the upper end of said bottom wall 35 upon which lip is seated the rearward end of a fuel delivery plate 37. Screws 9 may be utilized to detachably secure said delivery plate 37 to the bottom wall 35 of the tubular conduit 22. From the lip 36, the plate 37 extends upwardly and then curves inward into the lower portion of the firing opening 18, terminating a slight distance forward of the firebox inner sheet 14. It will be observed from Fig. 3 that the plate 37 fits against the lower marginal edge of the firing opening 18 in order to occupy the least amount

of space within the opening. A conveyor screw 38 is rotatably mounted within the tubular conduit 22 and urges the fuel upwardly into the casing 23 and thence forwardly onto the delivery plate 37 wherefrom the fuel drops onto a distributor, as will presently appear. The upper end of the conveyor screw 38 terminates below the upper edge 32 of the tubular conduit 22.

Due to the fact that the conveyor screw 38 10 delivers more fuel to one side of the delivery plate than the other, and also in order to make provisions for adjusting abnormal firebox conditions, means are provided for controlling the flow of fuel over the forward edge 39 of the delivery plate

15 37. This means includes a pair of deflector vanes 40, 41, one at each side of the firing opening 18. Each deflector 40, 41 is pivotally mounted rearward of the outer sheet 13 upon a respective upright pin 8 carried by the casing 23. In vertical 20 transverse cross section the deflector vanes 40, 41 are arcuate in shape so that upon assuming a retracted position, each vane will lie closely adjacent the corresponding side portion of the firing opening. Manual adjustment of the vanes 40, 41

25 is provided by the employment of hand screws 42 which are threaded into the flanges 25 of the casing. Each hand screw 42 is arranged to contact a lug 40a, 41a, of a respective vane 40, 41. Inward movement of the hand screws 42 causes the vanes 30 40, 41 to move inwardly across the delivery plate 37. To cause outward movement of the vanes 40, 41, hand screws 42 are moved outwardly, the fuel stream passing across the plate 37 and forcing the vanes outwardly.

35 The fuel distributor D is novel in construction and in its relation with the fuel feeding means and the locomotive firebox, as will now appear. At a point below the firing opening 18 and, preferably, above the cab deck 15, a thimble 50 is 40 passed through openings 51, 52 in the outer and inner sheets 13, 14, respectively, of the backhead 12. At its ends, the thimble 50 is beaded over the sheets 13, 14 and secured thereto by welding to form a water-tight joint. A distributor jet member 53 is passed through this thimble 50 and it 45 comprises a cylindrical shank 54 and a head portion 55, the front face 55a of which is semi-circular in horizontal cross section and disposed forward of the inner sheet 14.

50 Immediately rearward of the head portion 55, the jet member 53 is provided with a pair of oppositely extending lugs 56 arranged to abut against the inner bead of the thimble 50 upon tightening of the locking collar 57 over the 55 threaded outward portion of the cylindrical shank 54. The jet member is also supported upon the thimble 50 by a plurality of radial ribs 58 which fit within said thimble.

The outward portion of the shank 54 is 60 provided with threaded openings 59 into each of which is screwed a supply line 60 for admitting pressure fluid into a corresponding chambered passage 61 of the jet member 53. The passages 61 extend to the semi-circular front face 55a of the head portion 55 and issue blasts of pressure fluid through horizontally directed jet apertures 62. Below the level of the jet apertures 62 is the fuel receiving upper surface 63 of the distributing table 64. Ribs 65 on the surface 63 65 cooperate with the jet member in spreading the fuel over the grates 66. In order to provide an adequate support for the table 64, the jet member 53 is provided with a ledge 66 upon which rests the rearward portion of the table 64. Rearward of the ledge 66 and at each lateral extremity

of the jet member 53 is a curved lug 67 each of which is engaged by a hook 68 formed with the table 64.

In the operation of this device, the screw 38 urges fuel upwardly and forwardly through the conduit 22 and thence over the delivery plate 37 from which the fuel falls over the edge 39 downwardly through space and in loose form onto the table 64. From the table 64, the fuel is swept forwardly and laterally by the blasts of 10 pressure fluid issuing from the jet apertures 62. The delivery of fuel from the edge 39 of the delivery plate 37 may be controlled by proper manipulation of the vanes 40, 41.

Since the distributor D does not occupy any 15 space within the firing opening, and also because the delivery plate 37 and deflector vanes 40, 41 occupy very little of such space, it will be apparent to those skilled in the art that free access to the interior of the firebox 17 through the opening 18 may be gained readily by opening the firedoor 34. The stoker according to this invention may thus be readily installed on many existing locomotives with but a slight and inexpensive alteration of the locomotive firebox. 20

I claim:

1. In a furnace having a grate and an upright hollow water circulating wall provided with a firing opening disposed above said grate, said firing opening constituting a manhole for entrance into said furnace, a stoker for feeding fuel to said furnace comprising a conduit communicating with said firing opening, said conduit having a fuel supporting plate extending into said firing opening and closely adjacent the lower marginal edge thereof, means for urging fuel through said conduit and across said fuel supporting plate, said hollow wall being provided with a distributor opening spaced from said firing opening, and a distributor including a jet member and a distributing table, said jet member extending into the distributor opening of said hollow wall and being secured to such wall for supporting said distributor table in position beneath said firing opening to receive fuel discharged therefrom, said jet member being arranged to emit blasts of pressure fluid for projecting the fuel from said distributor table. 30

2. In a furnace having a grate and an upright hollow water circulating wall provided with a firing opening disposed above said grate, said firing opening constituting a manhole for entrance into said furnace, a stoker for feeding fuel to said furnace comprising a conduit communicating with said firing opening, said conduit having a fuel supporting plate extending into said firing opening and closely adjacent the lower marginal edge thereof, a pair of oppositely disposed deflector vanes pivotally mounted for movement across said fuel supporting plate, each of said deflector vanes being arranged for retraction to a position closely adjacent a respective side of said firing opening, means for urging fuel through said conduit and across said fuel supporting plate, said hollow wall being provided with a distributor opening spaced from said firing opening, and a distributor including a jet member and a distributing table, said jet member extending into the distributor opening of said hollow wall and being secured to such wall for supporting said distributor table in position beneath said firing opening to receive fuel discharged therefrom, said jet member being arranged to emit blasts of pressure fluid for projecting the fuel from said distributor table. 40
